UNITED STATES PATENT OFFICE.

ALEXANDER H. LIMONT, OF WATERBURY, CONNECTICUT, ASSIGNOR TO HOLMES, BOOTH & HAYDENS, OF NEW YORK, N. Y.

TUBING.

SPECIFICATION forming part of Letters Patent No. 408,728, dated August 13, 1889.

Application filed December 24, 1888. Serial No. 294,474. (No model.)

To all whom it may concern:

Be it known that I, ALEXANDER H. LIMONT, of Waterbury, in the county of New Haven and State of Connecticut, have invented a certain 5 new and useful Improvement in Tubing, of which the following is a specification.

My improvement relates to tubing of that kind which is especially intended for illuminating-fixtures provided with gas-burners and 10 electric lamps. Such tubing consists of an inner duct and an outer duct.

I will describe tubing embodying my present improvement, and then point out the novel features in a claim.

15 Figure 1 is a side view of tubing embodying my improvement. Fig. 2 is an end view thereof. Fig. 3 is an end view of a sheet or strip of metal, such as is used for manufacturing tubing of the kind shown in Figs. 1 and 20 2, and representing said sheet or strip as it appears at one stage in the manufacture of this tubing. Fig. 4 is an end view of this sheet or strip of metal bent to complete the tubing. The edges are not, however, represented as united in this figure, Fig. 2 being a 25 corresponding view illustrating the tubing as completed. Fig. 5 is a view corresponding to Fig. 4. In this view the outer duct is, however, made rectangular in the cross-section instead of circular in the cross-section, as it is 30 represented in Fig. 4. Fig. 6 is a side view of tubing of a slightly-modified form embodying my present improvement. Fig. 7 is an end view thereof. Fig. 8 is an end view of the 35 sheet or strip of metal as it appears at one stage in the manufacture of this form of tubing. Fig. 9 is an end view of the sheet or strip as finally bent into shape.

Similar letters of reference designate corresponding parts in all the figures.

Considering first the example of tubing illustrated by Figs. 1, 2, 3, 4, and 5, A designates a sheet or strip of metal which has parallel sides. It is first so bent that its middle portion a will assume the form of a semicircle, so 45 that the immediately-adjacent portions a' will be tangential to the semicircular portion and parallel with each other, and so that the edge portions a² will extend on curves outwardly and then parallel with the portions a', as may

be readily understood by reference to Fig. 3. Subsequently the straight portions a' will be bent to complete the circle, of which the portion a forms part, and the straight portions a² will be bent to form a larger circle. These 55 two circles may be seen completed in Fig. 4. The inner one A' is, it will be seen, eccentric to the larger and outer one A². It will be observed that in this example of my improvement the inner circle or duct A' is at one portion close to the inner surface of the larger and outer one A².

The bending may be done by any suitable tools or machinery. As these form no part of my improvement, I will not make further allusion to them.

The opposite edges a³ of the two ducts, where these ducts are contiguous, are united, and the side edges a⁴ of the sheet or strip are united. This may be done by brazing or soldering. 70 The tubing provided with the two ducts A' A² will then be completed in the form illustrated by Fig. 2.

In Fig. 5 I have shown a form of tubing in which the sheet or strip has the parallel portion a' bent to complete the circle of which the portion a is a part, and afterward has the side portion a² bent into the form of a rectangular tube. After this bending the opposite edges a⁴ will be united, as before explained in 80 connection with Fig. 4.

Obviously the inner duct A' may, if desired, be made of angular form in carrying out my improvement.

Turning now to Figs. 6, 7, 8, and 9, it will 85 be seen that the sheet or strip is at the middle bent to form a circle or duct A'. This may be best understood by reference to Fig. 8. Then the portions a³ of the sheet or strip immediately adjacent to the meeting edges of this 90 circle or duct A' are extended parallel to each other and radially to the said circle or duct a short distance. The side portions a² of the sheet or strip are then bent into circular form and form the outer duct A², as may be understood by reference to Fig. 9. In this example 95 it will be seen that the two ducts are concentric. The portions of the sheet or strip extending radially from the inner duct A' are united, and the side edges a⁴ are united by 100

brazing or soldering. The appearance of the finished tubing may best be understood by reference to Fig. 7.

Tubing embodying my improvement has **5** two distinct and separate ducts. Each may be used for a different purpose. For example, electric-light wires may be passed through one and gas through the other.

What I claim as my invention, and desire to secure by Letters Patent, is—

Tubing having two ducts, one within the other, and made from one sheet or strip of metal, substantially as specified.

ALEXANDER H. LIMONT.
